RAILWAY CROSSING SIGNAL

Filed Nov. 13, 1926

UNITED STATES PATENT OFFICE.

JOHN H. ESTES AND WILLIAM P. WILLIAMS, OF FORT WORTH, TEXAS.

RAILWAY-CROSSING SIGNAL.

Application filed November 13, 1926. Serial No. 148,220.

Our invention relates to signals and more particularly to railway and grade crossings of railways and street and road crossings; and the object is to provide devices for making the crossing of railway tracks safe and for preventing accidents by furnishing audible signals which are automatically operated by passing automobiles, or other wheeled vehicles. The advantage is that a passing vehicle will automatically actuate the signal devices in time to give the driver thereof notice that he is about to cross a railway track and this takes place whether a train is coming or not. Such notice if heeded will prevent numerous and serious accidents. Other objects and advantages will be fully explained in the following description and the invention will be more particularly pointed out in the claims.

Reference is had to the accompanying drawings which form a part of this application.

Fig. 1 is a side view of the signaling devices, viewing the devices from the side of a roadway.

Fig. 2 is a cross-section of the signaling devices.

Fig. 3 is a diagrammatic view, illustrating a crossing equipped with the signaling devices.

Similar characters of reference are used to indicate the same parts throughout the several views.

The drawings show a depressible board or platform 1 extending across a road way or street and supported by springs 2 of the required size and strength. The board 1 is re-inforced by cleats 3 attached to the underside thereof. The signaling devices are actuated by the board 1 and its connections. Slabs 4 of sheet metal or other material are attached to the board 1 to form approaches for the board 1. A vertical rack 5 is attached to the board 1 and a pinion 6 is mounted on a shaft 7. A wheel or spool 8 is rigid with the shaft 7. A cable 9 is attached at one end to the spool 8 and extended to the signaling devices. The board 1 is mounted over a trough or box-like structure 10 and the upper edges of the box limits the downward movement of the board 1 so that this board will go low enough to actuate the signaling devices but not low enough to interfere with the passing wheels of vehicles.

The cable 9 runs through a pipe 11 which

extends out of the box 10 to an underground casing 13 and under an idler 12 which is journaled in the casing 13. The cable 9 then runs upwardly within a pipe 15 or conduit to the signal box 14 and within the box 14. A bell or sounding device 16 is mounted within the box 14. A drum or spool 17 is journaled in the box 14 and the cable 9 is wound once around the drum 17 and then attached to a spring 18 which is attached to the box 14. The drum 17 carries beaters 19 which have flexible connection with the drum 17. When the cable 9 is actuated by the depression of the board 1, the cable will revolve the drum 17 and cause the beaters 19 to strike the bell 16 and as the wheels of the vehicle leave the board 1, the cable 9 will be drawn backwardly by the springs 2 so that the beaters 19 will strike the bell 16. The beaters 19 thus strike the bell on both movements of the cable 9.

What we claim is,—

1. Warning signal apparatus comprising means embedded in a highway near a railway crossing comprising an open-top box-like structure, a depressible board and springs supporting said board over said structure and normally slightly above the surface of the roadway, depending re-inforcing cleats attached to said board adapted to move downwardly within said box structure and some of said cleats moving downwardly on the outside of said structure, said board extending over the edges of said box structure for limiting the downward movement of said board, a signaling mechanism, a spool and a pinion provided with a shaft journaled in said box, a cable operatively connected with said signaling mechanism and extending within said box structure and attached to said spool, and a rack attached to said board and engaging said pinion for actuating said pinion automatically when vehicles cross said board.

2. Warning signal apparatus comprising means embedded in a highway near a railway crossing comprising an open-top box-like structure, a depressible board mounted above said structure with its ends projecting beyond said box structure and springs supporting said board normally slightly above said box structure, slabs attached to said board and resting on the highway to form approaches to said board, a signaling apparatus, a spool and a pinion rigid with each other and provided with a shaft journaled

in said box, a rack attached to said board and adapted to engage said pinion for actuating the same, a cable operatively connected to said signaling apparatus and extending within said box structure and attached to said spool, and means normally holding said cable taut but resilient to permit the operation of said cable by said rack and pinion.

In testimony whereof, we set our hands ¹⁰ this 19th day of October, 1926.

JOHN H. ESTES.
WILLIAM P. WILLIAMS.
